United States Patent Office

Des. 205,168
Patented June 28, 1966

205,168

FAN

Viktor Schreckengost, Cleveland Heights, Ohio, assignor
to The Murray Ohio Manufacturing Co., Nashville, Tenn., a corporation of Ohio

Filed July 1, 1965, Ser. No. 85,972

Term of patent 14 years

(Cl. D62—4)

Fig. 3

The appliance stand is shown in broken lines in the views and the drawings for illustrative purpose only.

I claim:

The ornamental design for a fan, substantially as shown and described.
